ELEVATOR DOOR SAFETY LOCK

Mauritz C. Holmstrom, St. Paul, Minn.

Application May 16, 1952, Serial No. 288,163

12 Claims. (Cl. 187—59)

1

This invention relates to an improvement in an elevator door safety lock and deals particularly with a lock for an elevator of the type employing vertically slidable doors.

Various types of safety locks have been employed for use on elevators of the type most commonly used as freight elevators. These safety locks are designed to prevent opening of the elevator doors at any time except when the elevator is level with that particular door opening. In view of the fact that it is sometimes desirable to be able to open the doors when the elevator is not level with the floor, the persons using the elevator remove these safety locks or render them useless. The present device is designed to render locks of this type more foolproof and to prevent those using the elevator from tampering with the safety devices and destroying their usefulness.

A feature of the present invention resides in the provision of an elevator lock employing an elongated rod fastened for movement with one of the doors and extending through the housing of the lock. When this rod is in place the door can not be opened unless the elevator is level with the door opening. If the rod is removed the elevator circuit is broken so that the elevator can not be used. As a result the device is relatively fool-proof and can not readily be rendered useless without considerable difficulty.

A further feature of the present invention resides in the provision of an elevator safety lock which is provided with a locking arm provided with a grooved end. This grooved end is designed to accommodate an end of the latch bar of the elevator door. When the latch bar is in latching position the locking arm is pivoted in a manner to close a circuit switch so that the elevator may be operated. When the locking arm is in this position the latch bar is held from vertical movement. As a result the door can not be opened while the circuit to the elevator is closed.

A further feature of the present invention lies in the provision of a means for holding the locking arm in circuit breaking position. As the elevator door is opened a rod secured to the door enters the groove of the locking arm and prevents this locking arm from pivoting into position to close the elevator circuit. Thus the operator of the elevator can not render the elevator operative while the door is open by manually swinging the locking arm into circuit closing position and wedging the arm in this position to hold the circuit closed.

An important feature of the present invention lies in the provision of a means for holding the

2

locking arm in circuit breaking position while the elevator door is open and in providing an additional means for breaking the circuit in the event the locking arm holding device is removed.

5 If the member which enters the groove of the locking arm to hold it in circuit breaking position is detached and removed, an additional circuit breaking switch is actuated to break the elevator circuit.

10 These and other objects and novel features of the present invention will be more clearly and fully set forth in the following specification and claims.

In the drawings forming a part of the specification:

15 Figure 1 is an elevation view of a portion of a pair of vertically slidable elevator doors, the elevator door frame, and the safety lock mechanism.

20 Figure 2 is a sectional view through a portion of the elevator door and frame, the position of the section being indicated by the line 2—2 of Figure 1.

25 Figure 3 is a perspective view of the lock housing, the operating mechanism having been removed therefrom.

Figure 4 is a sectional view through the safety lock, the position of the section being indicated by the line 4—4 of Figure 1.

Figure 5 is an elevation view of the safety lock mechanism, the housing cover plate having been removed.

Figure 6 is a sectional view similar to Figure 4 showing the lock in a different position.

30 Figure 7 is an elevation view of the lock with the housing cover removed, showing a modified form of construction.

Figure 8 is a sectional view through the apparatus, the position of the section being indicated by the line 8—8 of Figure 5.

40 The elevator door lock includes a supporting housing which is indicated in general by the numeral 10. This housing 10 is secured by bolts or other suitable means to the door guides 11 which guide the elevator doors in their vertical movement. Alternatively the housing 10 could be mounted upon the shaft wall 12 forming a part of the door frame, or in any other suitable manner.

45 The elevator door opening is normally closed by a pair of vertically slidable doors 13 and 14 which slide in the guides 11. Each door is substantially half the height of the door opening so as to close the opening when the upper door 13 is lowered and the lower door 14 is raised. Means

are provided, not illustrated, for connecting the doors 13 and 14 so that the doors will open and close in unison. Such arrangements are conventional in the art.

As illustrated in Figure 2 of the drawings, the guides 11 are provided with an inwardly facing channel 15 which is designed to accommodate an outwardly turned flange 16 of an angle member 17 mounted at the side edge of each door. The channel 15 slidably supports the flange 16 to permit free vertical movement of the doors.

In order to hold the doors closed, a pair of latch bars 19 are provided, one of which is illustrated in the drawings. In usual types of construction the two latch bars are connected to a lever which moves both latch bars into projected or retracted position simultaneously. When the latch bars 19 are projected laterally a right angularly extending extremity 20 engages over a wedge shaped lug 21 on the casing 10 to hold the door 14 from lowering. When the projecting end 20 of the latch bar 19 is in the position illustrated in Figure 5 of the drawings, this extremity 20 will strike the upper end of the lug 21 upon slight downward movement of the door 14, the lug arresting further movement of the door.

It is usual practice to provide a member such as the lug 21 at each side of the door opening so that each of the two latch bars 19 engages a corresponding shoulder and locks the door 14 from opening. Obviously the safety lock A may be used on either or both sides of the door opening. In the event the safety lock is mounted on the opposite side of the door opening from that illustrated in the drawings, the parts are correspondingly reversed.

The housing 10 is illustrated in Figure 3 of the drawings, the operating parts of the mechanism being omitted. As illustrated in Figure 3, the housing body includes a backing plate 22 from which projects a substantially L-shaped wall 23. The outer side of the housing is provided with an elongated vertically extending chamber 24 from which the wedge shaped projection 21 extends. A short partition wall 25 separates the elongated chamber 24 from the shorter chamber 26. An elongated tubular housing 27 is secured to the upper wall 29 of the housing, the tubular enclosure being illustrated in Figures 1, 4 and 5 of the drawings.

A locking arm 30 is pivotally supported at 31 to the base wall 22 of the housing 10. This locking arm 30 is of sufficient length to extend into close proximity with the upper extremity of the wedge shaped lug 21. The lower wall 32 of the shorter chamber 26 is apertured at 33 so that the locking arm 30 may extend through this wall 32. The upper end of the adjoining wall 34 of the longer chamber 24 is also apertured at 35 to accommodate a lateral extension 36 on the locking arm 30 and integral therewith.

The locking arm 30 is provided with a forwardly extending enlargement 37 which is slotted or bifurcated as indicated at 39. The slot walls are preferably curved so that the locking arm 30 may pivot within predetermined limits while still accommodating the angularly turned extremity 20 of the latch bar 19. The lateral extension 36 is apertured as indicated at 40 for a purpose which will be later described in detail.

A lever arm 41 is pivotally supported in the elongated chamber 24 of the housing 10 by means of a pivot 42 which extends through the outer wall 43 of the chamber 24 and through the partition wall 25. This lever arm 41 is pivotally con-

nected at 43 to a lever arm continuation 44 which is bifurcated at its outer end 45 to support a roller 46. A pivot 47 extends through the bifurcated ends of the extension 44 to rotatably support the roller 45. The pivot 43 is only employed for providing an initial adjustment of the angularity between the lever 41 and the extension 44. Once the position of the extension 44 relative to the lever 41 is determined a pin or key 49 may extend through the lever and the extension to hold these elements from relative pivotal movement. In other words, once the adjustment between these parts is made, the lever 41 and its extension 44 form an integral unit.

A latch bolt 50 is slidably supported by the housing 10 for movement toward or away from the base wall 22. Guides 51 illustrated in Figure 3 of the drawings guide the latch bolt in its sliding movement. The latch bolt 50 is provided with a bifurcated end 53 which is pivotally connected at 54 to the lever 41. Sufficient play is provided between the latch bolt and the lever to compensate for the varying angularity between these parts.

The latch bolt 50 is of proper proportions to extend into the aperture 40 on the locking arm 30. Thus when the lever 41 is in the position illustrated in Figure 4 of the drawings, the latch bolt extends into the locking arm 30 and holds this locking arm from pivotal movement. The lever 41 is actuated by a cam such as the cam 55 in Figure 6 of the drawings. When the roller 46 engages the cam 55, the lever 41 is pivoted in a counter-clockwise direction as viewed in Figures 4 and 6. When thus pivoted, the latch bolt 50 is withdrawn from the aperture 40 of the locking arm 30 so that the locking arm is free to pivot. A spring 56 is interposed between the lever 41 and the base plate 22 of the housing 10 so as to normally urge the latch bolt 50 into the locking arm aperture 40. The spring 56 also tends to urge the roller 46 into position for engagement with a cam such as 55.

The upper wall 29 and lower wall 32 of the smaller chamber 26 are provided with key hole shaped apertures 57 and 59 respectively. These apertures are substantially axially aligned with the tubular enclosure 27 mounted upon the upper wall 29 of the housing. An elongated rod 60 having a radially extending fin or flange 61 thereupon is slidably supported by the openings 57 and 59. The upper extremity of the rod 60 is provided with a disc shaped flange 62 which forms a bearing for the upper end of the rod 60 within the tubular enclosure 27 and which prevents the rod from being pulled downwardly out of the housing. The flange or fin 61 terminates at 63 in spaced relation to the lower end of the rod 60. However, the proportions are such that the pin or flange 61 is at all times engaged in at least one of the openings 57 or 59 so that the rod 60 can not rotate.

A bracket 64 is secured to the lower door 14 and is provided with a bearing 65 at its outer extremity through which the rod 60 extends. The lower end of the rod 60 is threaded to accommodate locking nuts 66 which hold the rod 60 in fixed relation to the bracket 64. Thus the rod 60 is secured for movement with the lower door 14. The bracket 64 is spaced beneath the latch bar 19 and the off-set end 20 of the latch bar is aligned with the flange 61 when the latch bar is in retracted position.

A switch 66 is mounted upon the partition wall 25 of the housing 10 and includes an operating

arm 67 which engages against the rod 60. The arm 67 holds the switch contacts closed at all times and opens only in the event the rod 60 is removed from the housing. This switch 66 thus provides a safety switch which is designed to break the circuit to the elevator motor or control in the event the safety switch is tampered with and the housing 27 and its enclosed rod 64 are detached.

A switch 69 is mounted upon the outer housing wall 43 and includes a switch actuating plunger 70 which is resiliently urged against a plunger actuating bracket 71 on the locking arm 30. The switch 69 is of the normally open type, but in practice the switch is normally held closed by the engagement of the plunger operating bracket 71 with the switch plunger 70. In other words, when the locking arm 30 is in the position shown in Figure 5 the switch 69 is closed. However, as soon as the locking arm 30 pivots into position to open the elevator doors, the switch 70 is opened and the circuit to the elevator motors or control is broken.

The operation of the safety switch is as follows:

As the elevator car moves into alignment with the door opening, a cam 55 engages the roller 46 which pivots the lever 41 from the position shown in Figure 4 of the drawings to the position shown in Figure 6. This action withdraws the latch bolt 50 from the aperture 40 of the locking arm 30. However, the locking arm 30 remains in locking position unless the latch bar 19 is manually operated.

When the latch bar 19 is pulled into retracted position, moving the latch bar to the right from the position shown in Figure 5 to the position shown in Figure 7, the locking arm 30 pivots in a counter-clockwise direction. A spring 72 normally biases the locking arm 30 toward the position shown in Figure 7. Upon moving the latch bar 19 into retracted position the angularly extending end 20 of the bar is moved out of alignment with the wedge shaped lug 21 so that the door 14 may be lowered and the upper door 13 simultaneously raised.

As the door 14 lowers the bracket 64 moves downwardly with the door, drawing the flanged rod 60 downwardly. The flange 61 of the rod 60 enters the slot 31 of the locking arm and holds this locking arm from pivotal movement. The lower end 63 of the fin or flange 61 is spaced closely above the off-set end 20 of the latch so that as soon as the latch end 20 leaves the slot 39 the fin 61 enters the slot and holds the locking arm 30 from pivotal movement. As long as the locking arm 30 is held in the position shown in Figure 7, the contacts of the switch 69 are open and the elevator cannot be moved.

Upon the closing of the doors 13 and 14, the rod 60 is raised until it is withdrawn from the slot 39 just as the off-set end 20 of the latch bar 19 enters the slot. When the doors are fully closed the latch bar 19 is moved laterally into locking position as shown in Figure 5, this action pivoting the locking arm 30 in a counter-clockwise direction. The control to the elevator motor is then in circuit and the switch contacts of switch 69 are closed.

As soon as the elevator car is moved sufficiently to disengage the roller 46 from the cam 55 the latch bolt 50 is engaged in the locking arm to hold the locking arm from pivotal movement. In the event the elevator passes a door opening, the lever 41 merely unlatches the locking arm tem-

porarily, but relatches the same as soon as the door opening is past.

The foregoing description applies to a construction not employing a movable cam. In some installations, the cam 55 is movable in the shaft, and only projects into the path of the cam roller 46 when a selected floor is reached.

For installations of this type, the lever 41 is extended substantially beneath the latch bolt 50, while for fixed cam arrangements the lever 41 may be cut off just below the latch bolt 50. A switch 75 is mounted in the elongated chamber 24, and is provided with a plunger 76 in the path of movement of the lever 41. When the cam roller is out of engagement with the movable cam 55, the lever 41 is in the position shown in Figure 4 and the switch to the elevator controls or motor is closed. When the cam 55 engages the roller 46, the lever arm 41 is pivoted into the position shown in Figure 6. In this position the latch bolt 50 is unlatched, and the switch contacts of switch 75 are opened, thus preventing operation of the elevator.

A circuit diagram has not been shown in view of the simplicity of the circuit, and further due to the fact that the circuits may be arranged directly in the elevator motor circuit or may act through suitable relays. In the fixed cam structure, the switches 66 and 69 may be in series so that when either is opened, the elevator cannot operate. When a movable cam arrangement is provided, the third switch 75 may also be in series with the switches 66 and 69, and the circuit to the elevator may be broken when any of the three switches is opened.

In accordance with the patent statutes, I have described the principles of construction and operation of my elevator door safety lock, and while I have endeavored to set forth the best embodiments thereof, I desire to have it understood that obvious changes may be made within the scope of the following claims without departing from the spirit of my invention.

I claim:

1. A safety lock for vertically movable elevator doors having a laterally slidable latch bar having an angular extremity, the lock including a support, a locking arm pivotally supported by said support, a vertically grooved end in said locking bar designed to accommodate the angular extremity of said latch bar, a fixed projection engageable beneath the extremity of said latch bar in latched position thereof, a lever arm pivotally supported by said support, a roller supported by one end of said lever arm, and a latch bolt connected to the other end of said lever arm, said latch bolt being engageable with said locking arm in latched position thereof for holding said locking arm from pivotal movement and holding said latch bar in latched position from lateral movement.

2. A safety lock for elevators having vertically movable elevator doors and laterally movable latch bars thereupon, the lock including a support, a locking arm pivotally supported by said support, means on the free end of said locking arm designed to accommodate the extremity of said latch bar and to be pivoted thereby, said latch bar being movable between two extreme positions, said bar extremity acting to pivot said locking arm between two extreme positions, a locking member engageable with said latch bar extremity in one extreme position of said latch bar to hold said latch bar from vertical movement, a lever pivotally secured to said housing,

cam means for pivoting said lever, a latch bolt connected to said lever for actuation thereby, said latch bolt in one extreme position engaging said locking arm when said locking arm and said latch bar are in said one extreme position.

3. The structure described in claim 2 and including means movable with the elevator door for holding said locking arm in said other extreme position when said door is at least partially open.

4. The structure described in claim 2 and including a member slidably supported by said housing and connected to the elevator door for movement therewith, said member engaging said locking arm in its other extreme position and holding said locking arm from movement toward said one extreme position.

5. The structure described in claim 2 and including a control switch actuated by said locking arm.

6. An elevator safety lock for use in conjunction with elevators having vertically movable elevator doors and laterally movable latch bars, the lock including a support, a locking arm movably supported upon said support for movement between two extreme positions, said locking arm having a grooved portion designed to accommodate the extremity of the latch bar, the latch bar being movable between two extreme positions to move the locking arm together therewith, an elongated slidably member secured to the door for movement in unison therewith, said slidably member being supported by said support, means on said slidably member engageable in said notched portion of said locking arm upon opening movement of the door for holding said locking arm in one extreme position, means for holding said extremity of the latch bar from vertical movement when said locking arm is in its other extreme position, and switch means on said sup-

port actuated by said locking arm upon movement thereof from one extreme position to the other.

7. The structure described in claim 6 and in which said locking arm is pivotally secured to said support.

8. The structure described in claim 6 and including switch means engageable with said slidably means and actuated by disengagement of said slidably means from said support.

9. The structure described in claim 6 and including a lever pivotally supported to said support, a latch bolt movable into and out of engagement with said locking arm and connected to said lever for actuation thereby.

10. The structure described in claim 6 and including a cam lever pivotally supported by said support, a latch bolt supported by said support and engageable and disengageable with said locking arm, and actuated by said cam lever.

11. The structure described in claim 6 and including a lever pivotally secured to said support, a cam roller secured to said lever for actuating the same, and a switch actuated by said lever.

12. The structure described in claim 6 and including a lever pivotally secured to said housing, a latch bolt engageable and disengageable with said locking arm, means connecting said latch bolt and said lever for actuation in unison, a second switch means, and means on said lever for actuating said switch means.
